PERAMBULATOR

Martha Fehre, New York, N. Y.

Application January 26, 1933, Serial No. 653,573

1 Claim. (Cl. 219—19)

This invention relates to improvements in perambulators, or baby carriages, and particularly to a vehicle of this character having means for heating the handle portions of the frame. Its 5 principal object is to provide a form of equipment in combination with the vehicle structure which will, when the carriage is in motion, generate sufficient heat to the handle grips so that the hands of a person grasping the same will be 10 comfortably warmed thereby.

Modern methods as applied to the care of infants require that the child shall be kept in the open air for long periods each day. This is generally accomplished by wheeling the child about 15 in a vehicle of the class above designated. Now, several hours spent in pushing such a vehicle about on a day when the temperature is below freezing, is a very uncomfortable procedure under ordinary circumstances, and in many cases 20 the person attending the infant would be tempted, or forced by reason of cold hands to shorten the period of airing, or to postpone it until another day; all of which is bad for the child whose 25 health is endangered by this lack of proper care.

It is the purpose of this invention to provide a 30 means for maintaining the handle grips at a comfortable temperature and to accomplish this by the use of a simple and inexpensive apparatus installed on the frame of the carriage. This apparatus is automatic in action and requires practically no care or attention other than occasional lubrication.

The foregoing objects and features and other 35 advantages of the invention are fully set forth and explained in the following specification and claim, and illustrated in the accompanying drawing, in which:

Fig. 1 shows a side view of a baby carriage with the apparatus attached.

Fig. 2 shows an enlarged fragmentary section on the line 2—2 of Figure 1.

Fig. 3 shows a further enlarged cross section on the line 3—3 of Figure 2.

Referring now to Figure 1 of the drawing; an 45 electric generator 10 is shown mounted on the axle 11 of the carriage 12. This generator has a gear 13 which is in mesh with a drive gear 14 attached to the wheel 15 of the carriage. Current is produced when the carriage is moved along in

the usual manner. The generator is then rotated by the gear 14. The current passes upward along the wire 16 which is, preferably, within the handle bars 17.

Referring now to Figure 2, the grip elements 18 are made of any suitable material, such as thin metal or the like, oxidized to give a desirable color. These grips are sustained by the cross rod 19 having the nuts 20 at its extremities.

Within the grip elements and supported on the 10 rod 19 is an insulator 20 of porcelain or similar material—see Figure 3. A channel 21 has perforations 22 and within the channel a resistance coil 23 is positioned. This coil is in circuit with the positive wire 16—see Figure 2—and the negative wire 24 which leads back to the generator. A switch 25 is conveniently placed as shown so that the current may be shut off when desired. Air spaces 26 extend along the interior of the grip 15 elements and distribute heat received through the 20 perforations 22.

While the invention is shown and described in its preferred general form; it may be subjected to minor changes in detail without prejudice to the principle involved, and it is therefore broadly claimed within the spirit and scope of the appended claim.

Having thus described the invention, what is claimed as new and desired to be secured by Letters Patent of the United States, is as follows: 30

In a device of the class described, the combination of a heating unit with a carriage handle, and comprising grip elements, a rod supporting the latter, an insulator mounted on said rod and being made with two upwardly projecting flanges at 35 its top, said flanges forming a channel between themselves and being provided with perforations in their longitudinally extending surfaces, a resistance coil disposed in said channel and serving as a positive wire, and with a negative wire co-acting 40 with said resistance coil; the insulator being of a size relative to the gripping elements so as to form spaces therebetween adapted to co-operate with the perforations in the flanges leading to said channel for the conveyance of heat from 45 the resistance coil, disposed in the latter, to the gripping elements, and a switch for controlling the heating element.

MARTHA FEHRE.
